US00D853662S

(12) **United States Design Patent** (10) **Patent No.:** **US D853,662 S**
(45) **Date of Patent:** **** Jul. 9, 2019**

(54) **HUMMINGBIRD FEEDER**

(71) Applicant: **Syll Innovations, LLC**, Poughkeepsie, NY (US)

(72) Inventors: **Lisa Marie Ellis**, Marlboro, NY (US); **Dennis Gerard Ellis**, Marlboro, NY (US)

(73) Assignee: **Syll Innovations, LLC**, Poughkeepsie, NY (US)

(**) Term: **15 Years**

(21) Appl. No.: **29/663,228**

(22) Filed: **Sep. 13, 2018**

Related U.S. Application Data

(62) Division of application No. 29/573,349, filed on Aug. 4, 2016, now Pat. No. Des. 831,899.

(57) **CLAIM**

The ornamental design for a hummingbird feeder, as shown and described.

DESCRIPTION

FIG. 1 is a front perspective view of a hummingbird feeder according to our design;

FIG. 2 is an environmental front perspective view of the hummingbird feeder of FIG. 1;

FIG. 3 is a front elevation view of the hummingbird feeder;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The environmental broken line showing of a base feeder in FIG. 2 depicts an exemplary attachable component for purposes of illustration and forms no part of the design claim.

1 Claim, 6 Drawing Sheets
